UNITED STATES PATENT OFFICE.

JOHN EMANUEL JOHNSON AND CHARLES H. OSLUND, OF WORCESTER, MASSACHUSETTS, ASSIGNORS TO THE O & J MACHINE COMPANY, OF WORCESTER, MASSACHUSETTS, A CORPORATION OF MASSACHUSETTS.

COOLING AND MIXING MACHINE.

Application filed October 27, 1923, Serial No. 671,238. Renewed December 4, 1925.

This invention relates to a machine for taking bottles from a crowning or other sealing machine, subjecting them to a series of baths of water for the purpose of either 5 cooling or heating them, as may be desired, and thoroughly mixing the contents during that process. In the manufacture and putting up of such commodities as ketchup the bottles are heated to a high degree at the 10 time when they are crowned. With this machine they can be taken automatically from the crowning machine and subjected to three baths of water for cooling purposes, each bath being a little cooler than the one 15 before and at the same time the bottles can be rotated and tilted along their axes so that the contents will be thoroughly mixed while they are being cooled. They can be discharged from the machine in a cool 20 enough condition so that they can be packed in cases and shipped immediately, if desired.

The invention also involves an improved mechanism for conveying the bottles back 25 and forth through the tanks, an improved relationship of the tanks, means for keeping them at different temperatures, and mechanism for operating the endless chain conveyors, as well as the details of the conveyors and sprockets for driving the same 30 and means for controlling the admission of the bottles into the machine.

Additional objects and advantages of the invention will appear hereinafter.

Reference is to be had to the accompanying drawings, in which

Fig. 1 is a plan of the receiving end of the machine;

Fig. 2 is a similar plan of the discharge 40 end of the machine on the same scale, it being understood that a large part of the machine is omitted between these two views;

Fig. 3 is an elevation of the means for feeding the bottles into the machine from 45 the crowner and of the sprocket mechanism at the receiving end of the machine, looking in the direction of the arrow 3 in Fig. 1;

Fig. 4 is a side elevation of the machine 50 partly broken away to show interior construction;

Fig. 5 is a sectional view on the line 5—5 of Fig. 4;

Fig. 6 is a side view of one of the sprocket wheels;

Fig. 7 is a diametrical sectional view of 55 the same;

Fig. 8 is a side view of a portion of the device on an enlarged scale;

Fig. 9 is an enlarged plan of a part of the machine showing the tipping of the 60 bottles from horizontal to inclined position;

Fig. 10 is a sectional view on the line 10—10 of Fig. 9; and

Fig. 11 is a sectional view on the line 11—11 of Fig. 1, these two figures showing 65 two positions of the bottles.

As stated above, this machine is capable of general use either for cooling or heating bottles or other articles that have been 70 crowned or otherwise sealed but we have designed it particularly for use in taking ketchup bottles which have been crowned in a highly heated state in a crowning machine, introducing them in a vertical state, resting on their bottoms, into a tank of 75 water somewhat cooler than the contents of the bottles so as to reduce the temperature thereof but not cool enough to crack the glass, tilting them over on their sides in this water and conveying them along therein in 80 such a way as to roll them and thereby mix the contents thoroughly while they are traversing the bath. Then I provide means for tilting the bottles into vertical position and shifting them from this bath into a second 85 one at the end of their travel. This second bath is heated to a lower temperature so as to reduce the temperature of the goods still further and yet not present any danger of 90 breaking the bottles. The bottles are rolled along in this bath and then brought to upright position again which, it will be observed further, assists in mixing the contents, and then carried on into a third bath at a still lower temperature to cool them 95 down to normal and further mix the contents in the same way. These three baths are arranged parallel with each other and the bottles are conveyed through them by 100 three endless chains, the two on the outside taking them in the same direction and the center one taking them back so that they are received at one end of the machine and discharged at the other. This will indicate the 105 general nature of the machine.

We have provided a general large tank 10 divided into three compartments 11, 12 and 13 longitudinally. These compartments

are provided with water and each one constitutes a separate tank. They are heated by water or steam entering the several tanks separately through pipes 14, 15 and 16. 5 The tanks are heated to different temperatures for the purpose above described and the heat is distributed to the water in the tanks by arranging pipes or coils in the bottom of each tank communicating with the 10 several supply pipes as indicated more especially in Fig. 5 or in any other desired way.

The machine can be run in any desired way but we have shown a motor 20 which by 15 pinion, not shown, on its shaft operates a gear 21 fixed on a shaft 22 provided with a pinion 23 for driving a gear 24 running loose on a bushing 90 which is keyed to a shaft 25. Keyed to bushing 90 is a friction 20 disc 91 having a leather disc 92 fixed to it. By means of springs 93 mounted on studs 94 and the friction device the gear 24 drives the shaft 25. On this shaft 25 there is a pinion 26 driving a gear 27 keyed on the 25 main shaft 28 of the machine which is located at the discharge end thereof. On this main shaft 28 there are three sprocket wheels 33, 40 and 41.

The first sprocket wheel has a hub 29 provided with a disc 30. On this disc are arranged three bolts 31 which pass through ar- 30 cuate slots 32 in an annular plate 33. Therefore it will be seen that this annular plate can be adjusted circumferentially on the hub 35 of the sprocket wheel. On this hub are lugs 34 provided with screws 35 entering lugs 36 projecting from the inner side of the annular plate 33 so that by turning one in and the other out this plate can be adjusted and 40 then the bolts 31 tightened up to hold it in adjusted position. On this annular plate 33 are sprocket teeth 37 so that the plate with the other parts just described constitutes the first sprocket wheel. It will be 45 seen that the teeth of this sprocket wheel are adjustable around the shaft to a certain degree.

At the other end of the shaft is another sprocket wheel designated 40 of the same 50 character as the sprocket wheel just described. Intermediate between these two sprocket wheels is a third sprocket wheel 41 which is of the ordinary kind and not having any adjustment preferably but free on 55 the shaft.

Over each of these sprocket wheels passes a chain. The three chains are just alike and only one of them will be described. Each one of these chains is made up of a series of links 60 43 each comprising a flat plate 44 on the top of the link proper and having a spacing plate 45 perpendicular thereto located at the center thereof or at any rate at equal distances apart. In general, the links are connected 65 together by providing each one with an in-

tegral pair of hooks 46 at one end and with a transverse projecting stud 47 at the other entering the next hooks. Under the plates 44 are spaces 48 that receive the teeth 37 of the sprocket wheel and each link has a trans- 70 verse wall 49. It will be seen therefore that the three chains 50, 51 and 52 in the three tanks 11, 12 and 13 are operated by three sprocket wheels. The two outer chains 50 and 52 are operated in the same direction to 75 bring the bottles toward the shaft 28 on the upper strand of the chain. The central chain 51 is moved in the opposite direction to carry the bottles back as will appear.

At the other end of the machine there is a shaft 54 parallel with the shaft 28 and having upon it two sprocket wheels 55 and 56 in line with the sprocket wheels 33 and 40 and receiving the same chains by which they are rotated positively. They are fixed on this shaft 54 and turn it. Also fixed on this shaft 54 is a gear 57 meshing with a gear 58 on a shaft 59 on which is a sprocket wheel 60 like the sprocket wheels 33 and 40 and opposite the sprocket wheel 41 which is loose on its shaft. On account of this gearing the sprocket wheel 60 rotates in the opposite direction to the sprocket wheels 55 and 56 and this is the wheel which positively rotates the endless chain 51 and moves it in a direction opposite to that in which the other two chains move.

At this end of the machine there is a bevel gear 61 on the shaft 54 which drives a vertical shaft 62 on which there is a cam wheel 63 having a certain number of projections, in the present instance six, for operating a lever 64 six times for each rotation of the shaft 62. Also on the end of the shaft 54 there is a gear 65 which operates a longitudinal shaft 66 having a sprocket wheel 67 for operating a feed belt 68. The relation between the gears 61, 65 and the number of cam projections on the cam 63 is such that for each bottle fed out of the crowning machine on the endless feed belt 68 the lever 64 will be operated back and forth. The end of this lever engages a roll 70 mounted on a lever 71. This latter lever has a spring 72 for moving it back and a latch 73 on the end for preventing the discharge of a bottle from the conveyor 68 except when it is drawn back, which is accomplished periodically by the operation of the cam 63. This permits the bottles to be fed from the conveyor 68.

The latch 73 is pivoted on the end of the lever 71. One end of the latch 73 projects into the conveyor in front of the bottles. The other end is held in a groove 74 in a stationary casting 95 by means of an adjustable spring 98 mounted on the lever 71. This locks the lever 71 against moving back. The bottle hits the projecting latch 73 throwing the other end out of the groove 74 in the casting 120

95 and releasing the lever 71 so it can be moved back by the spring 72 whenever the cam 63 turns to a position to allow that motion. Ordinarily the lever 71 does not move 5 if there are no bottles on the conveyor 68 because it remains locked by the latch 73. The conveyor 68 is higher than the conveyor 50 and the bottles are tipped over by gravity and fall on their sides on rubber pads 96 between two of the plates 45 of the conveyor 50.

The part of this conveyor 50 which is in position to receive the bottles from the conveyor 68 is elevated as shown in Fig. 4. The 15 bottles are moved along horizontally on the conveyor 50 for a slight distance and then the conveyor is allowed to descend by a guide below which supports it so that the bottles are brought down into the water of the first 20 tank 11. As the conveyor 50 continues to move forward they are rolled along for mixing the contents, as above explained. The bottles having passed on down in the tank 11 which is filled with hot water, but 25 considerably cooler than the contents of the bottles, they will roll along in this tank for a considerable period of time while the contents are being mixed and cooled.

As they come to the other end of the tank 30 the chain is brought up to an elevated position and then the bottles continue to roll along with their necks resting on a horizontal ledge or guide plate 77 and their butts against a vertical wall 78. The former 35 gradually rises and forces them up as shown in Fig. 10, to a slightly inclined position. This guide plate continues to project further into the path of the bottles until it tips them up into the vertical position as shown in 40 Fig. 9 at the left.

Then there is a slanting deflecting wall 79 located across the conveyor and over the tops of the plates 45 which slides the bottles over to the side as shown in Fig. 2. They are 45 then taken up by a rotating gate or turn-stile 80 fixed on a vertical shaft 81 and driven from one of the two adjacent chains by the plates 45 thereon engaging teeth 82 on the shaft 81.

50 This gate necessarily operates exactly in synchronism with the chains 50 and 51 and its projecting points register with the spacing plates 45 thereof on both sides so that it moves the bottles around from one chain conveyor to the other, takes them from between two plates 45 on one and deposits them exactly between two plates 45 on the other. The bottles are guided by plates 85 to prevent their moving out of contact with the gate as 55 they pass around. Of course the two conveyors are at the same elevation at this point.

The bottles pass on the second conveyor at 51 in vertical position and then meet a guide plate 76 which first forces them over to a

slightly inclined position as shown in detail in Fig. 11. This guide plate continues to project further until the bottles are tipped over into horizontal position. They are then 50 rolled along in the second tank 12, which is filled with cooler water, until they come to a deflector 79 just as before and are carried by another gate 80 over to the third conveyor 55 52 in the same way as described above. Here the bottles have been righted to vertical position and have been deposited on the conveyor 52 right side up resting on their bottoms. They then meet another set of plates 76 and 77 and turn over into slanting position and roll back to the opposite end of the machine, in a tank 13 of cold water. At the 60 end of this tank they hit guides 77 and 78 and are brought to vertical position when the third deflector 79 forces them out of the machine into a receiver 89 from which they can 65 be taken by hand or conveyor, as may be desired.

The bottles are cooled down to normal by this time and their contents thoroughly 70 mixed. It will be seen therefore that in this way the machine provides for automatically feeding the bottles from the crowning machine to the point of discharge, cooling them gradually but constantly and thoroughly 75 mixing the contents practically all the time. The mixing is done not only by rolling the bottles along but by tilting the bottles up to vertical position three times during the process and tipping them down from vertical to 80 nearly horizontal position three times also.

Although we have illustrated and described only a single form of the invention we are aware of the fact that modifications 85 can be made therein by any person skilled in the art without departing from the scope of the invention as expressed in the claims.

Therefore we do not wish to be limited to the details of construction herein shown and described but what we do claim is:—

1. In a conveying machine for bottles or the like, the combination with a plurality of tanks adapted to contain water, of a conveyor in each tank, means for operating the conveyors in the adjacent tanks in opposite directions, whereby the bottles or the like 110 can be conveyed along one tank to the end thereof, and movable mechanical means actuated by the motion of the conveyors for transferring the bottles from one conveyor to the other so that they can be transferred 115 back substantially to the starting point.

2. In a conveying machine for bottles and the like, the combination of a plurality of parallel tanks, a corresponding series of parallel conveyors in said tanks adapted to receive the bottles and carry them along in the tanks immersed in the water therein, means for delivering the bottles to the receiving end of the first conveyor in horizontal position so as to be carried through 125 130

- the water in the tank in that position, means for bringing the bottles back to upright position while still on said first conveyor, means for removing the bottles automatically from the first conveyor while in upright position and transferring them to the receiving end of the second conveyor which is located adjacent to the discharge end of the first conveyor, and means whereby the course of the bottles on the second conveyor is substantially the same as that on the first conveyor but the direction of motion is opposite thereto.
3. In a machine of the character described, the combination of two conveyors, with a deflector plate at the discharge end of one of the conveyors for deflecting the articles therefrom sideways as the conveyor travels along in a path, said conveyor having spacing plates between which the articles are adapted to be located thereon, the second conveyor having its receiving portion at substantially the same elevation as the discharge portion of the first conveyor, a turnstile between the two conveyors adjacent to said deflector, said turnstile having projecting points at the same distance apart as the spacing plates on the conveyors, whereby when an article is forced out sideways by the deflector from the first conveyor it will be received between two of the points on the turnstile and the further motion of the conveyors will push it along and turn the turnstile to start the article around the turnstile toward the second conveyor.
4. In a machine of the character described, the combination of two parallel endless conveyors for receiving bottles or the like, with a deflector plate at the discharge end of one of the conveyors for deflecting the bottles therefrom sideways as the conveyor travels along in a straight path, said conveyor having spacing plates between which the bottles are adapted to be located thereon, the second conveyor being located parallel with the first and running in the opposite direction and having its receiving portion at the same elevation as the discharge portion of the first conveyor, a turnstile between the two conveyors adjacent to said deflector, said turnstile having projecting points at the same distance apart as the spacing plates on the conveyors, whereby when a bottle is forced out sideways by the deflector from the first conveyor it will be received between two of the points on the turnstile and the further motion of the conveyors will push that bottle along and turn the turnstile to start the bottle around the turnstile toward the second conveyor, and the feeding motion of the first conveyor forward another step to feed another bottle out sideways will have a corresponding effect and will also tend to force the first mentioned bottle further around, said turnstile being provided with a guard plate around it to prevent the bottles from moving out of contact with it as the turnstile rotates.
5. In a machine of the character described, the combination with three parallel tanks having guides therein, of three parallel endless conveyors located in the respective tanks, means for moving the two outside conveyors in the same direction and for moving the middle conveyor in the opposite direction, means for introducing bottles or the like on the receiving end of the first conveyor, means for sliding the bottles off the first conveyor sideways for delivering them in the same plane on the receiving end of the second conveyor, means for sliding the bottles off the discharge end of the second conveyor and on the receiving end of the third conveyor, and means for sliding the bottles off the third conveyor sideways to discharge them from the machine.
6. In a machine of the character described, the combination with three parallel tanks having guides therein, of three parallel endless conveyors located in the respective tanks, means for moving the two outside conveyors in the same direction and for moving the middle conveyor in the opposite direction, means for introducing bottles or the like on the receiving end of the first conveyor, means whereby the bottles are tipped over into horizontal position on said conveyor and rolled along through the tank thereby, means whereby the bottles are brought to an upright position on the conveyor at the discharge end, means for sliding the bottles off the first conveyor sideways for delivering them in the same plane on the receiving end of the second conveyor, the second conveyor having means for tilting the bottles over and rolling them along through its tank and then bringing them to upright position at the end, means for sliding the bottles off the discharge end of the second conveyor and on the receiving end of the third conveyor, the third conveyor having means for tilting the bottles over into inclined position and rolling them along through its tank, means for righting the bottles at the discharge end thereof, and means for sliding the bottles off the third conveyor sideways to discharge them from the machine.
7. In a machine of the character described, the combination with three parallel tanks, of three parallel endless conveyors located in said tanks, a driving shaft, a pair of driving sprocket wheels fixed on said driving shaft and connected with two of the conveyors for driving them positively in the same direction, a third sprocket wheel loosely mounted on the driving shaft connected with the other conveyor, a parallel shaft at the other end of the machine hav-

- ing two sprocket wheels fixed thereto for receiving the first two conveyors, a third shaft, means for rotating the third shaft from the second shaft in the opposite direction, and a sprocket wheel fixed to the third shaft engaging the third conveyor for positively moving it in the direction opposite to that of the first two conveyors.
8. In a machine of the character described, the combination with three parallel tanks, of three parallel endless conveyors located in said tanks, a driving shaft, a pair of driving sprocket wheels fixed on said driving shaft and connected with the two outside conveyors for driving them positively in the same direction, a third sprocket wheel loosely mounted on the driving shaft connected with the middle conveyor, a parallel shaft at the other end of the machine having two sprocket wheels fixed thereto for receiving the outside conveyors, a third shaft, means for rotating the third shaft from the second shaft in the opposite direction, and a sprocket wheel fixed to the third shaft engaging the middle conveyor for positively moving it in the direction opposite to that of the other conveyors, each of said conveyors comprising a series of links pivoted together, each link having a spacing plate projecting at right angles therefrom, whereby the articles to be received and conveyed can be located between two adjacent spacing plates.
9. In a machine of the character described, the combination with three parallel tanks, of three parallel endless conveyors located in said tanks, a driving shaft, a pair of driving sprocket wheels fixed on said driving shaft and connected with the two outside conveyors for driving them positively in the same direction, a third sprocket wheel loosely mounted on the driving shaft connected with the middle conveyor, a parallel shaft at the other end of the machine having two sprocket wheels receiving the outside conveyors fixed to the second shaft for rotating it, a third shaft, means for rotating the third shaft from the second shaft in the opposite direction, and a sprocket wheel fixed to the third shaft engaging the middle conveyor for positively moving it in the direction opposite to that of the other conveyors, the two first mentioned sprocket wheels and the last mentioned sprocket wheel each comprising a hub fixed on its driving shaft, and an annular plate secured to said hub and adjustable circumferentially and provided with sprocket teeth thereon.
10. In a conveyor, the combination with a tank, a driving shaft, a sprocket wheel on the driving shaft, an endless conveyor chain engaging the sprocket wheel to be operated thereby, a companion sprocket wheel for supporting the other end of the chain, a second shaft on which the sprocket wheel is fixed, a cam wheel connected with the second shaft to be operated in synchronism therewith, a feed belt for conveying articles to the conveyor chain, means connected with the second shaft for operating the feed belt at a definite relation to the speed of the second shaft, a stop adjacent to the feed belt, and means operated by the cam wheel for periodically removing the stop to permit individual articles to pass over the end of the feed belt on the chain conveyor.
11. The combination with a cooling tank and a conveyor therein for receiving bottles or the like thereon, of a feed belt for conveying the bottles thereto and depositing them over its end thereon, a lever, a latch on the lever projecting into the path of a bottle on the belt and adapted to be actuated by such bottle to unlock the lever, said latch having means for normally locking the lever against motion in a direction to permit the bottles to pass off the belt, yielding means tending constantly to move the lever to a position in which the latch projects into the path of the bottles, and means operated by said conveyor for periodically and positively holding the lever in a position to prevent the discharge of bottles from the belt except at the moments when the conveyor is in exact position to receive them.
12. The combination with a cooling tank and a conveyor therein for receiving bottles or the like thereon, of a feed belt for conveying the bottles thereto and depositing them over its end thereon, a lever, and a latch on the lever projecting into the path of a bottle on the belt and adapted to be actuated by such bottle to unlock the lever, said latch having means for normally locking the lever against motion in a direction to permit the bottles to pass off the belt.
- In testimony whereof we have hereunto affixed our signatures.

JOHN EMANUEL JOHNSON.
CHARLES H. OSLUND.
